Patented July 22, 1975

236,001

FLOW REGULATOR

Stellan S. Akesson and Karel E. Pruner, Jonkoping,
Sweden, assignors to Aktiebolaget Svenska Flaktfab-
riken, Nacka, Sweden

Continuation-in-part of abandoned design application Ser.
No. 283,636, Aug. 25, 1972. This application Oct. 29,
1974, Ser. No. 518,224

Claims priority, application Sweden Aug. 17, 1972

Term of patent 14 years

Int. Cl. D23—04

U.S. Cl. D23—151

FIG. 1.

FIG. 2.

FIG.3.

FIG.4.

FIG.5.

FIG.6.

FIG. 1 is a front elevational view of a flow regulator embodying our new design;

FIG. 2 is a rear elevational view thereof;

FIG. 3 is a top plan view thereof;

FIG. 4 is a bottom plan view thereof;

FIG. 5 is a right side elevational view thereof, the left side being a mirror image of the side shown; and

FIG. 6 is a sectional view taken along lines 6-6 of FIG. 1.

This is a continuation-in-part of design application Ser. No. 283,636, filed Aug. 25, 1972, now abandoned.

We claim:

The ornamental design for a flow regulator, substantially as shown and described.
